CONCRETE FORM SPACER

Robert J. Colgan, Wayne, and Anthony De
Gange, Philadelphia, Pa.

Application January 13, 1932, Serial No. 586,320.

Renewed January 11, 1934

5 Claims. (Cl. 25—131)

The present invention relates to concrete construction and more particularly to the spacing of forms used in connection with the pouring of concrete or other material.

5 In pouring concrete to make walls, piers, columns, and other structures it is necessary to provide forms of the proper shape and dimensions for the purpose intended. An important part of the construction is the correct spacing of forms so that the poured concrete will be of the required uniform width while such spacing is maintained until the concrete has set. Various complicated devices for spacing these forms have been tried but have been found impractical because of 10 the added cost of labor for installation; the high cost of the devices, and the fact that such devices have to be removed after the concrete has set causing damage which necessitates unsightly patching.

20 Some of the objects of the present invention are to provide an improved device for spacing forms during the pouring of concrete; to provide a simple and inexpensive spacing device which can be assembled in operative position with a minimum 25 of labor; to provide a spacing device for concrete forms which does not have to be removed after the concrete has set; to provide spacing means for forms wherein bars of scrap material can be 30 efficiently associated with certain furnished parts to make a complete unitary spacer; to provide a form spacer which functions effectively without causing holes, depressions, or breaks in the face of the wall or other structure when the forms are removed; to provide a spacer for concrete forms 35 which becomes a permanent part of the wall or other structure and eliminates therefore the possibility of irregular surfaces; to provide a spacer device which can be installed quickly and without the loss of time incident to devices which have 40 been sporadically tried in an attempt to solve the problem; and to provide other improvements as will hereinafter appear.

In the accompanying drawing Fig. 1 represents a sectional elevation of two spaced form boards 45 showing one form of the present invention in operative position; Fig. 2 represents a sectional elevation of a concrete wall showing the invention embodied therein after the removal of the board forms; Fig. 3 represents a perspective of one end 50 of a spacer bar capped with the end anchoring socket; and Fig. 4 represents one form of anchoring element as furnished for use.

55 Referring to the drawing one form of the present invention consists of two anchoring sockets 10 and a spacer bar 11 having its ends respec-

tively seated in said sockets 10 as supports for the bar 11. Each socket 10 is preferably of stamped metal, though other methods of making may be employed, and consists of a base 12 of suitable shape having a plurality of laterally disposed prongs 13 projecting generally parallel from one side of the base 12. Also integral with the base 12 are a plurality of lugs 14 which in the initial forming lie in the plane of the base 12 and expose the base without obstruction to a hammer or other implement to cause the prongs 13 to penetrate a board form for concrete. The base 12 provides a flat bearing surface on its outer side against which abuts the end of the spacer bar 11 and is there held by bending the lugs 14 against the side of the bar 11 in the form of a retaining socket.

In order to avoid holes in the finished concrete and to expose a very minimum part of the spacer elements after the form boards have been removed, it is preferable to provide spaces 15 at the respective ends of the bar so that grout can fill in and practically embed the whole spacer device. To that end each of the prongs 13 is formed with a tab 16 which is bent inwardly to parallel the base 12 at such a distance therefrom as will give a large enough space to allow grout to enter and adequately fill it. Thus the three tabs 16 will all lie in the same plane equally spaced from the base 12 and when the prongs 13 are driven into a form board the tabs 16 act as limit stops abutting the face of the board and holding the socket in suitable spaced relation to such board.

35 In use the sockets 10 are shipped in bulk and have the form such as shown in Fig. 4. The spacer bars 11 are generally cut to length at the job because of the great variation in width of walls, columns and the like. When the distance between the two form boards, shown at 17, is known the bars 11 to be used with the sockets 10 are cut to give a length equal to the distance between the bases 12 of two oppositely located sockets 10. The sockets 10 are arranged in pairs, the socket element of one pair being mounted on the face of one form board opposite the other 45 socket element of the opposite form board and both elements being substantially in the same horizontal plane. The socket elements are quickly placed because one hammer blow generally forces the prongs 13 into the boards and 50 brings the limit tabs 16 into face contact with the boards. The bars 11 are now placed between the bearing seats of the bases 12 and fastened by bending the lugs 14 into gripping relation with the sides of the bar. When the concrete mix is 55

oured into the form it will surround the bar 11 and sockets 10 while also entering and filling the spaces 15. Therefore the only parts of the spacer device not covered by the material are the protruding ends of the prongs 13 and the relatively small area of the stops 16. The ends of the prongs 13 being of thin material can easily be cut off flush with the face of the wall and in the following pointing operation both these exposed flush ends and the portion of the stops 16 can be completely concealed. Attention is also directed to the ingenious spacing of the ends of the rod 11 from the plane of the wall faces and providing a structure which permits the concrete or grout to fill in this space and thereby completely insure against exposure of the rod ends. The disadvantage in having the steel rod ends exposed on the face of the finished wall is that corrosion almost immediately takes place and staining of the wall takes place.

It will now be apparent that a complete unitary spacing device has been devised readily placed in position between the frame boards which receive concrete and can be so placed with a minimum of labor and in exact spacing relation by unskilled help. Furthermore by the device of the present invention the spacing elements do not have to be removed after the concrete is poured and as they can be manufactured very cheaply the loss by leaving them in the concrete is inappreciable.

While only a single form is shown in which this invention may be embodied, it is to be understood that the invention is not limited to any specific construction, but might be applied to various forms without departing from the spirit of the invention or the scope of the appended claims.

Having thus described our invention, we claim:

1. A spacer for concrete forms comprising a bar, sockets for receiving the respective ends of

said bar, and prongs on each socket for anchoring said sockets to the inner faces respectively of two opposite form members.

2. A spacer for concrete forms comprising a bar, sockets for receiving the respective ends of said bar, prongs on each socket for anchoring said sockets to the inner faces respectively of two opposite form members, and stops to limit the penetration of said prongs into said members.

3. A spacer for concrete forms comprising a bar, sockets for receiving the respective ends of said bar, prongs on each socket for anchoring said sockets to the inner faces respectively of two opposite form members, and means to form spaces at opposite ends of said bar between said sockets and said members.

4. A spacer for concrete forms comprising a bar, and two base members to seat against the respective ends of said bars, lugs attached to said base members and arranged to be bent outwardly to form sockets for receiving the ends of said rod, and prongs attached to said base members and extending therefrom in the opposite direction from said lugs to penetrate a form board and anchor each socket.

5. A spacer for concrete forms comprising a bar, and two base members to seat against the respective ends of said bars, lugs attached to said base members and arranged to be bent outwardly to form sockets for receiving the ends of said rod, prongs attached to said base members and extending therefrom in the opposite direction from said lugs to penetrate a form board and anchor each socket, and tabs bent from said base members to form stops to limit the penetration of said prongs.
